UNITED STATES PATENT OFFICE

ERIK L. KRAM, OF CHICAGO, ILLINOIS

BOOKSTAND

Application filed January 27, 1930. Serial No. 423,667.

This invention relates to book stands and it has for its object providing suitable apparatus for supporting a number of books on end or edge, when it is desired to have the books on a desk or table, for convenience in using intermittently.

Of the accompanying drawings, Fig. 1 is a perspective view of the apparatus; Fig. 2 is an enlarged fractional plan view of the arrangement of the openings in the frame, a portion being in section; Fig. 3 is a sectional view along the line 3—3 of Fig. 1; and Fig. 4 is an elevation of a central supporting member.

15 The object of my invention is to provide a suitable apparatus for setting on the desk or table, so that books may be supported conveniently for use, and a particular object of the invention is to provide such apparatus arranged so that the books, when supported, will not only be suitably supported on end, but they will be so supported that the leaves or papers contained therein will not drop down or become warped out of shape or the 25 like. This is prevented by means of a support which has resiliently yielding sides, so that the books can be conveniently placed in the stand but the sides will be held snugly together by the yielding sides when the book is 30 in place.

The apparatus comprises any suitable frame 5 which, in this instance, is composed of three members, a top plate 6 and a relatively narrow bottom plate 7 extending along 35 each long edge of the plate 6, and having rubber feet 8, one at each corner of the frame. Between these plates are middle plates comprising holding members 10 which also are relatively narrow and are positioned along 40 the two edges of the plate 6. The plate 6 has a downwardly extending flange 11, and the other plates have suitable flanges, as indicated, by means of which the plates are fixed firmly together either by welding, riveting, 45 or otherwise.

End supports 12 are provided. These are preferably formed from heavy wire or bars bent into shape and having notches 13 for holding the supports in place. The legs of the 50 supports are passed down through openings

14 in the top plate and openings 15 in the central plate. The legs are formed so that the feet are wider apart normally than the holes, and are sprung together when put in place, and finally the notches 13 coact with 55 the edges of the holes 15, so as to hold the supports firmly in place, and, yet, so that they may be easily removed. The openings have an enlarged portion 16, so that the ends of the rods may be readily passed through these 60 openings and a smaller portion 17 in which the ends of the rods fit snugly as they spread apart. In this manner, the rods may be quickly passed into position through the lower holes, and they may then be released 65 and, perhaps, pulled upwardly slightly until the notches 13 register with and coact with the outer edges of the holes.

The frame 5 may be made as long as may be desired, preferably from 12 to 18 inches, and 70 as many holes as are desired may be inserted therein. Obviously, as many supports may be used as it is desired, and placed in the various holes where desired. In this instance, I show 12 holes, and for convenience every fourth 75 hole is indicated in any suitable manner, such as by means of a small opening 18.

One or more of the supports 12 is provided with resiliently yielding strips or bands 20. Preferably, there are one or two of these 80 bands for the support, as may be desired. Preferably, the inner supports have two strips, and the ends are fixed to the support in any suitable manner, such as by means of end pieces 21 which are fixed to the supports and have flanges 22. One end of the bands are riveted to the flanges 22, but the other ends are resiliently held against the flanges, so that the legs of the supports may be pressed together when being positioned, 85 or the ends of the bands can slide on the flanges when the bands are pressed inwardly by the books. These bands are bowed as indicated in Fig. 1, and are sufficiently yielding to be pressed inwardly by the books when 90 the books are put into place. As a consequence, when the books are in place, they will be closed, and yet may be easily withdrawn from the support.

There may be as many inner supports as 100

may be desired, each preferably having two spaced bands. And on one or both end supports a band 20 may be mounted, projecting inwardly, so that it also will assist in pressing the books together.

5 I claim as my invention:

1. A book stand comprising a top plate and a bottom plate and a middle plate, the top plate having a flange on each long edge 10 extending downwardly, the bottom plate being spaced from the top plate and having a flange on each long edge extending upward, one of the latter flanges being fixed to the inner surface of the flange of the top plate, 15 and the middle plate being positioned between the flanges of the bottom plate and with its opposite long edges fixed to said bottom plate, said middle plate being spaced from both plates, and a flange extending upwardly from the inner edge of the middle plate and being fixed to the top plate, said top and middle plates having vertically 20 registering openings therethrough, and a book support extending upwardly from the top plate and having a leg extending through a pair of the registering holes.

2. A book stand as claimed in claim 1, comprising similar bottom and middle plates fixed similarly to the other downwardly extending flange of said top plate, and said top and middle plates having similar vertical registering holes, and said support having another similar leg extending through a pair of the last mentioned registering holes.

3. A book stand as claimed in claim 1, comprising similar bottom and middle plates fixed similarly to the other downwardly extending flange of said top plate, said top and middle plates having similar vertical registering holes, said support having another similar leg extending through a pair of the last mentioned registering holes, a block positioned between each pair of said bottom and middle plates near each end thereof, and 45 a foot support connected to each of said blocks by means passing through said bottom plates.

4. A book stand comprising a top plate, supports for the plate extending along and 50 beneath two opposite edges of the plate, said supports comprising two spaced strips, said plate having a row of spaced openings over each support, and the upper strip of each support having a row of openings registering vertically with the corresponding openings in the plate, a plurality of U-shaped book supports mounted with their legs in said openings, a yielding resilient band extending across one of said supports, and one 55 end being fastened to one of the legs of the support.

5. A book stand comprising a top plate, supports for the plate extending along and beneath two opposite edges of the plate, 65 said supports comprising two spaced strips,

said plate having a row of spaced openings over each support, and the upper strip of each support having a row of openings registering vertically with the corresponding openings in the plate, a plurality of U-shaped book supports mounted with their legs in said openings, and a pair of spaced resilient bands extending across one of said supports from one leg to the other, one end of each band being fixed to one leg and the other ends being slidably associated with the other leg.

6. A book stand comprising a plate, a plurality of spaced supports extending upwardly from said plate, and a resilient band fixed by one end to one side of one of said supports, and extending to adjacent the other side of the support, said band at its central portion extending outwardly away from the plane of the support.

7. A book stand comprising a top plate, a frame extending along and beneath each of two opposite edges of the plate, said frame comprising two spaced strips, said plate having a row of spaced openings over each frame, and the upper strip of each frame having a row of openings registering vertically with the corresponding openings in the plate, a plurality of U-shaped book supports mounted with their legs in said openings, and a yielding resilient band extending across one of said supports, one end being fastened to one of the legs of the support.

In testimony whereof, I hereunto set my hand.

ERIK L. KRAG.
